CLAIM

The ornamental design for a children's toy structure, as shown and described.

DESCRIPTION

FIG. 1 is a front, top, right perspective view of a children's toy structure according to my present invention.

FIG. 2 is a bottom, rear, left perspective view thereof.

FIG. 3 is a front elevation view thereof.

FIG. 4 is a rear elevation view thereof.

FIG. 5 is a right side elevation view thereof.

FIG. 6 is a left side elevation view thereof.

FIG. 7 is a top plan view thereof; and,

FIG. 8 is a bottom plan view thereof.

Portions not illustrated herein form no part of the claimed design. The dash-dash broken lines depict portions of the children's toy structure that form no part of the claimed design.
